(57) **CLAIM**

The ornamental design for a post rack as shown and described.

DESCRIPTION

FIG. 1 is a front isometric view of the post rack.

FIG. 2 is a rear isometric view of the post rack of FIG. 1.

FIG. 3 is a front view of the post rack of FIG. 1.

FIG. 4 is a back view of the post rack of FIG. 1.

FIG. 5 is a left side view of the post rack of FIG. 1.

FIG. 6 is a right side view of the post rack of FIG. 1.

FIG. 7 is a top view of the post rack of FIG. 1; and,

FIG. 8 is a bottom view of the post rack of FIG. 1.

The broken lines show portions of the post rack which form no part of the claimed design.

1 Claim, 7 Drawing Sheets
